UNITED STATES PATENT OFFICE.

JOSEPH ZUBATY, OF FLINT, MICHIGAN, ASSIGNOR TO A C SPARK PLUG COMPANY, OF FLINT, MICHIGAN, A COMPANY OF MICHIGAN.

INSTRUMENT ASSEMBLY.

Application filed January 29, 1926. Serial No. 84,792.

This invention relates to instrument assemblies and particularly to a dash board assembly for automobiles so constructed as to afford effective illumination of the instruments.

The invention consists in the provision of a cover plate for an instrument or a plurality of instruments, the cover plate being provided with an aperture for the display of each of the instrument dials and with a reflecting device about the aperture for directing light upon the dial. A light source is arranged at the rear of the cover plate so as to be shielded from the eyes of the observer and casts a portion of its light upon the reflector. In order that the lighting of the dials may be effectively accomplished, I have found it preferable to make the reflector discontinuous so that an opening is provided for the direct projection of rays from the light source upon the reflector. I have also found it preferable to make the reflector of rearwardly flaring form to better project light upon the dial.

I also make provision in my assembly for the projection of light upon surrounding objects. Thus I have provided an aperture in the flange by which my cover plate is secured to the instrument panel, the aperture being so located that light rays are projected therethrough upon the floor of the driver's compartment.

In the drawings:

Figure 1 is a front elevation of my instrument assembly.

Figure 2 is a section on line 2—2 of Figure 1.

Figure 3 is a view taken on line 3—3 of Figure 1.

The reference character 2 indicates an instrument panel of the type used upon automobiles. This may be of any desired material or configuration. The panel is provided with a plurality of apertures for exposing the dials of instruments 4 secured to the panel by any suitable clamping means, not shown. 6 indicates a cover plate for the instruments, this cover plate being provided with a peripheral flange 8 having an out-turned edge portion 10 adapted to lie against the front face of the instrument panel and to be secured thereto in any convenient way. The cover 6 is provided with apertures aligned with the apertures in the

instrument panel to permit inspection of the instrument dials. Around each of these apertures I have provided a reflector 12, preferably consisting of a rearwardly flared flange. This flange may conveniently be formed as an integral part of the cover 6 by bending or swaging a portion of the material which would ordinarily be removed in providing the display apertures. The flanges 12 are discontinuous to provide passages 14 through which rays from the light source 16 mounted on the instrument board at the rear of the cover plate may be directly projected. In order to conserve the energy of the light source it is desirable that the inner surface of the cover plate be treated to constitute an efficient reflector; thus it may be painted white or nickel-plated.

With the above construction it is apparent that the light 16 which is shielded from the eyes of the observer by the cover plate will project portions of its rays through passages 14 upon the reflectors 12 which direct the light upon the instrument dials. The inclination of the reflectors 12 is such that no rays can be directly reflected therefrom into the eyes of the observer. At the same time the exterior of the cover plate presents an attractive unbroken surface.

If desired a portion of the light from the source 16 may be made use of for general illumination. I have provided an opening 18 in the flange 8 through which light may be cast upon the floor of the driver's compartment for the illumination of the transmission lock and operating levers.

While I have described the instruments as arranged behind individual apertures in the instrument boards, it is obvious that they may be grouped for display through a single aperture or otherwise arranged without departing from the spirit of my invention in its broader aspect.

I claim:

1. An instrument assembly comprising a plurality of instruments having dials, a cover for said instruments having openings for the inspection of said dials, rearwardly flaring flanges arranged about said openings arranged to reflect light upon said dials, said flanges being discontinuous providing openings for the admission of light to said flanges and dials, and a source of light at

the rear of said cover and between the last named openings.

2. The combination of an instrument board and an instrument assembly mounted on said board including instruments having dials, a cover for said instruments having openings for the inspection of the dials, means for holding the cover plate spaced forwardly of the instrument board, said means being apertured, a light source at the rear of said cover plate adapted to illuminate said instruments and to project a portion of the light through said aperture for the illumination of the driver's compartment, and reflecting devices arranged about the inspection openings for reflecting light upon the instrument dials.

3. The combination as set forth in claim 2, said reflecting device comprising flanges formed about said openings, said flanges being discontinuous to afford passages for the projection of light upon the dials.

4. The combination of an instrument panel, an instrument mounted on said panel, a cover plate, a flange on said cover plate for securing the plate to the panel and holding it spaced therefrom, said cover plate being provided with an opening for the inspection of the instrument dial, and with an inwardly turned flange around the opening adapted to reflect light upon said dial, a source of light shielded by said cover plate and adapted to illuminate said dial, and an opening in said first named flange for the projection of light rays for general illumination.

5. The combination as set forth in claim 4, said inwardly turned flange being discontinuous to provide a passage for the admis-

sion of light from said source, said passage facing said source.

6. A cover plate for an instrument having an opening for the inspection of the dial and provided with an inwardly turned rearwardly flaring flange about said opening for reflecting light upon said dial.

7. The combination set forth in claim 6, said flange being discontinuous to permit the passage of rays of light for illuminating the dial.

8. In an automobile instrument board assembly, the combination of an instrument, a cover plate for the instrument, said cover plate being provided with an aperture for the display of the instrument dial, said aperture having an inwardly turned flange, the flange being discontinuous to provide an opening, a light source for illuminating the dial at the rear of the face plate, said opening in the flange facing the light source to permit the passage of rays to the dial.

9. An automobile instrument board, a plurality of instruments mounted on the board, a cover plate for the instruments mounted on the board independently of the instruments, said cover plate being provided with apertures for the display of the instrument dials, said apertures having inwardly turned flanges, the flanges being discontinuous to provide openings therein, a light source for illuminating the dials at the rear of the cover plate, the openings in the flanges facing the light source to permit the passage of rays of light to the dials.

In testimony whereof I affix my signature.

JOSEPH ZUBATY.
